UNITED STATES PATENT OFFICE.

CHARLES HEYMANN, OF PARIS, FRANCE.

DEVICE FOR ATTACHING STIFFENERS TO TROUSERS.

1,091,842.

Specification of Letters Patent. Patented Mar. 31, 1914.

Application filed April 1, 1913. Serial No. 758,093.

To all whom it may concern:

Be it known that I, CHARLES HEYMANN, citizen of the Republic of France, residing at 39 Rue de Paradis, Paris, in the Republic 5 of France, have invented new and useful Improvements in Devices for Attaching Stiffeners to Trousers, of which the following is a specification.

This invention relates to an improved device 10 for attaching stiffeners to trousers.

According to the invention the trouser creases are stiffened and maintained by means of a light strip of fabric provided with a very thin sheet of gutta percha by 15 means of which the strip is caused to adhere to the inside of the trousers crease by applying a hot iron on the outside of the trousers. This assures permanent shapeliness of the crease. In order to properly position the 20 strip in the trousers a support, forming part of this invention, and consisting of a bar provided with points along its edge is used, as will hereinafter be described. Said bar has preferably a lozenge shaped cross section 25 and is used in connection with a bar having a triangular cross section and affording a convenient support for applying the stiffening band at the inside of the trousers leg.

In the annexed drawing given by way of 30 example: Figure 1 is an elevation of the lozenge shaped bar. Fig. 2 is a cross section thereof. Figs. 3 and 4 are respectively an elevation and a cross section of the triangular bar. Fig. 5 is a perspective view showing a part of the bars with the trousers leg 35 in position thereon for applying the stiffening strip. Fig. 6 is a detail showing a partial cross section of a trousers leg with the stiffening band secured therein.

40 A strip of fabric *c* made of silk or any other suitable light fabric is first folded lengthwise on a support, not shown, having a V shaped cross section, it is then dressed with an adhesive preparation preferably a 45 rubber solution, by means of which a thin sheet of gutta percha *d* is stuck on the outer surface of said strip. The thin gutta percha *d* is fixed by a cold process to the fabric of the strip. The prepared strip is 50 then laid astride on the sharp edge of a bar *a* made of wood or any other suitable material, having a lozenge shaped cross section, said edge being provided with projecting points *b* adapted to pass through the strip 55 and hold it in place on the bar. The bar *a*

is then introduced into the leg *e* of the trousers, the crease *g* of the trousers, which is preferably first made by an iron, being applied along the relatively sharp edge provided with the points of the bar, the inner 60 face of the trousers, along the crease, being thus applied against the strip of gutta percha *d*. The bar *a* with the leg of the trousers thereon is then laid against the inclined face of a bar *a* of a triangular shape, 65 as shown in Fig. 5. The angles *h* and *i* of the bars *a*, *a* are such that when the bars are suitably superimposed, the bar *a* is firmly supported and has its upper face *j* in a horizontal plane. A hot iron is then 70 passed over the fabric of the trousers on said face *j* and, the bar *a* having been turned over, the hot iron is next passed over the fabric against the opposite face *m*. The heat and pressure of the iron causes the material of the trousers to adhere to the strip of gutta percha and consequently to the strip of fabric *c*. The crease thus formed is 75 very resistant and permanent.

By means of the arrangement of bars just 80 described, the iron may be displaced over the trousers very easily and conveniently. The sharp angle *h* of the bar *a* permits of obtaining an even crease of a very clean appearance. The method is inexpensive and is 85 rapid of execution.

The invention is not strictly limited to the examples described and may obviously be varied within the scope of the appended 90 claim.

Having now described my invention, what I claim as new and desire to secure by Letters Patent is:

A device for applying a stiffening strip to the inside of the crease in the leg of trousers, 95 comprising a bar having a sharp edge and provided with projecting points on said edge and a supporting bar having an inclined face such that one of the faces of the first named bar, on either side of the sharp edge, 100 lies in a substantially horizontal position when the first named bar is placed upon the inclined face of the supporting bar.

In testimony whereof I have signed my name to this specification in the presence of 105 two subscribing witnesses.

CHARLES HEYMANN.
